(57) **CLAIM**

The ornamental design for a quick mount non-destructive temporary mounting system, as shown and described.

DESCRIPTION

FIG. 1 is a perspective view of a quick mount non-destructive temporary mounting system;

FIG. 2 is a left side elevational view thereof; the right side is a mirror image thereof.

FIG. 3 is a front elevational view thereof;

FIG. 4 is a rear elevational view thereof;

FIG. 5 is a top plan view thereof; and,

FIG. 6 is a bottom plan view thereof.

The broken line showing of environment in the drawings is included for the purpose of illustrating only and forms no part of the claimed design.
